(57) **CLAIM**

The ornamental design for a multi-functional wireless charger, as shown and described.

DESCRIPTION

FIG. 1 is a perspective view of a multi-functional wireless charger showing our present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a schematic view of FIG. 1 in an open state; and,

FIG. 9 is a schematic view of FIG. 1 in an use state.

The broken lines and the shaded areas bounded by broken lines depict portions of the multi-functional wireless charger that form no part of the claimed design.

1 Claim, 9 Drawing Sheets
